JAMES A. KEYES, OF NEW YORK, N. Y., ASSIGNOR TO UNITED WRAPPING MACHINE COMPANY, OF CHICAGO, ILLINOIS, A CORPORATION OF ILLINOIS.

MACHINE FOR WRAPPING ARTICLES.

No. 852,961.

Specification of Letters Patent.

Patented May 7, 1907.

Application filed November 12, 1903. Serial No. 180,833.

To all whom it may concern:

Be it known that I, JAMES A. KEYES, a citizen of the United States, and a resident of New York city, in the county and State of New York, have invented certain new and useful Improvements in Machines for Wrapping Articles, of which the following is a specification, taken in connection with the accompanying drawings, which form a part of the same.

This invention relates to machines for wrapping articles and relates especially to machines in which the articles are wrapped in mold wheels being transferred from one mold wheel to another during the wrapping operation.

In the accompanying drawings in which the same reference numeral refers to similar parts in the several figures Figure 1 is a side view partly in section of a machine embodying this invention. Fig. 2 is a similar view, the line of section being substantially through the center of the mold wheel. Fig. 3 is a detail showing the paper feeder. Fig. 4 is a perspective view of the same. Figs. 5, 6, 7, 8, 9, 10 and 11 show details of the folding and tucking mechanism and its operation in wrapping an article. Fig. 12 shows a detail of the wrapper strips.

In the embodiment of the invention shown in the drawings, a rigid frame 1 is provided supporting the main shaft 2 in suitable bearings and also supporting the cam shaft 37 in similar bearings so as to be parallel to the main shaft. The sprocket chain 70 driven by the sprocket wheel 69 on the main shaft engages a similar sprocket wheel 83 on the cam shaft so as to rotate these two shafts in unison. The folding wheel 51 and the tucker wheel 81 are secured upon the shafts 30, 31 and are rotated intermittently so as to bring the molds in these wheels into alinement, the articles being forced into the molds of the folder wheel together with the wrappers fed thereto by the paper feeder. The folding wheel 51 and the tucker wheel 81 will both be referred to throughout the specification broadly as wrapping wheels for they each perform different steps in the wrapping of the article.

The paper feeder for feeding the wrappers to the folding wheel comprises an auxiliary feed for withdrawing the paper from suitable reels mounted at the top of the machine in

any desired way. This auxiliary feed may be in the form of the feed roll 100 mounted upon the shaft 99 and preferably rotated at a speed slightly in excess of the desired speed of the wrapper by a suitable belt 101. A suitable looper is preferably employed to assist in the feed of the paper and the looper indicated in Figs. 1 and 2 may be used. This comprises a looper roll 98 pivoted about the arm 102 which swings about the pin 97 in the upper part 16 of the frame. This looper roll when moved into the position indicated in Fig. 2 forms a loop between the auxiliary feed roll 100 and the idle roll mounted upon the pin 97 and as indicated in Fig. 1 the looper arm 26 connects the lower part 103 of the looper arm with the crank 116 secured to the shaft 22. The paper strip passes between the cutter roll 25 and the coöperating feed roll 24, although any other desired mechanism may be employed to feed forward and sever the separate wrappers from the paper strips. The cutter roll is indicated as formed with the knife 80 having yielding guards on either side of the same pressed outward by the springs 78, this knife coöperating with a suitable cutting face 79 mounted in the channel 77 in the roll 24. As indicated, the knife and guards are mounted in the channel 76.

The cutter roll and feed roll are geared together by the coöperating gears 21 and the cutter roll is also preferably provided with the alining members 73 each of which as indicated in Fig. 3, is formed with a point 72 which is normally retracted beneath the surface of the roll 25 by the spring 74 acting on the head 75. This alining member is, however, provided with the pin 89 which cooperates with the cam 86 held in stationary position so that when the pin rides up on the cam the point 72 of the aliner is protruded beyond the surface of the roll. The feed roll 24 is formed with a hole 87 to accommodate the point 72 and also is formed with the depression 117 by which the grip between the two rolls is interrupted at the time the alining member acts. The alining member cooperates with the presser 18 mounted upon the presser bar 84 which is held downward by the spring 19 so that the pressers engage the paper strips as they pass over the cutter roll, these pressers being formed with suitable slots 88 through which the points of the

aliners may protrude. A suitable pivoted latch 17 is pivoted about the arm 85 on the presser bar and this latch as is indicated in Fig. 1 is adapted to engage the pin 83 so that the pressers may be held out of contact with the cutter roll.

Two strips of paper may be used to wrap the articles and either the outer wrapper 107 or the inner wrapper 108 may be printed with suitable advertising matter or in other ways. When these wrappers are printed the alining holes 83 are formed in them which always bear a fixed relation to the printed matter on the wrappers and to the proper line of severance between them. The blanks 106 are preferably not entirely punched out of the paper strips but are joined by tongues 105 as indicated in Fig. 12. The paper strips fed by the auxiliary feeder are engaged by the cutter roll and feed roll by which they are severed into separate wrappers and the wrappers are brought into accurate alinement before being fed forward by the alining pins which are protruded by the mechanism described so as to engage the holes 83 in the strips and protruding through the slots 88 in the pressers slightly adjust the longitudinal position of the wrappers while the grip of the cutter roll and feed roll is released by reason of the depression 117 (see Fig. 4). At this time, also, the movement of the looper roll furnishes enough slack so that the paper strips can readily be drawn forward and absolute alinement secured. When this is effected the further rotation of the cutter roll and feed roll positively grip the paper, feed it forward the length of the wrapper and the cutter 80 thereupon severs it. The double wrapper 20 is by this means supplied at the proper intervals in front of the mold in the folding wheel, as indicated in Fig. 1. As indicated in that figure, the feed roll is rotated by a suitable sprocket chain 104 which is driven by a sprocket on the cam shaft 37, although the paper feeder may be operated in any other desired way in conjunction with the other mechanism.

The tucking wheel 81 is rigidly secured to the shaft 31 which is mounted in suitable bearings in the frame and this wheel may be provided with any desired number of suitable molds about its periphery. These mold are formed by the plates 49 removably secured at one side of the molds by the screws or bolts 57. The movable sides 50 are preferably pivoted about the pins 82 in the wheel. As seen in Figs. 1, 7 and 9 these sides 50 are formed with the arms 55 which are spring pressed into engagement with the stationary cam 94 on the shaft 31 which cam may be secured to a part of the frame not shown, a suitable spring 56 being indicated for this purpose. The folding wheel 51 is similarly secured to the shaft 30 and is provided in a similar way with molds about its periphery,

these molds having the removable plates 49 at one side and the movable sides 50 at the opposite side of each mold controlled by the cam 95. It will be seen that the removable plates in the two wheels are in alinement and that by employing suitable washers or other means the position of these plates may be readily altered in the two wheels, so that molds may be formed of different width. The two wheels are geared together by the gears 58, 59 secured to the shafts and the folding wheel is intermittently rotated by a Geneva stop movement operated by a suitable roll 66 on the arm 65 secured to the cam shaft 37. This roll engages the radial slots 115 in the star wheel 114 indicated in Fig. 2, so as to give an intermittent rotation to the mold wheels, the circular segment 166 serving to engage the circular recesses in the star wheel to hold the mold wheels in alinement at the several stations.

The two mold wheels are provided with plungers in each of the molds, the plungers 48 being preferably rigidly mounted on the plunger rods 52 which pass through the mold wheel and in this way the opposite plungers are rigidly connected and are operated in unison. These plungers are preferably formed with convex working faces, as indicated, so that their working faces substantially correspond to the circumference of the wheels and secure the complete ejection of articles therefrom. The plungers of the two wheels are positively moved at intervals by the ejector pins 63, 64 on the ejector 42 which is pivoted about the point 41 at the bottom of the frame. This ejector is provided with a suitable roll 39 engaged by the ejector cam 40 which gives a simultaneous movement to the two pins thus throwing all the horizontally located plunger rods and the four plungers attached thereto to one side to transfer and eject the articles. The articles to be wrapped are supplied in any desired way and may be brought forward along the upper run 11 of a suitable belt, the lower run of this belt being indicated as 15. The articles are fed into the folding wheel at intervals by the feed plate 12, which as is indicated is mounted on a suitable lever 13 pivoted about the point 4, see Fig. 2. This lever is connected at the point 163 by the link 62 with the ejector so that the ejector and feed plate move in unison. Before the feed plate operates, however, the support 14 is moved toward the wheel, this support being mounted on the lever 3 pivoted about the pin 4 and operated by the cam 71 on the main shaft which engages a suitable roll 5 on the lever. The guide 10 is pivoted on the upper end 6 of this lever and has a suitable projection 9 which engages the curved end of an arm 8 mounted on the bar 7 of the frame. As this support moves upward the guide is allowed to drop downward as soon as the

portion 9 moves away from the coöperating part 8 and thus the article is guided both above and below at the time the feed plate forces it forward into the mold in the folding wheel.

The wrapper 20 which may be a double wrapper, as indicated, is supplied at the proper intervals in front of the mold of the folding wheel and the article forced into the mold by the feed plate carries the wrapper with it, the ends of the wrapper projecting outward on either side of the article, the length of these projecting ends being substantially as indicated in Fig. 5. The oscillating folder 28 engages the upper projecting end of the wrapper 20 and folds it upon the article 89, as indicated in Fig. 5. This folder 28 consists of a curved plate mounted upon the arm 29 pivoted about the shaft 30 and operated by the folder cam 38 on the cam shaft. This cam engages a roll 35 on the folder lever 34 pivoted about the pin 36 and the link 33 connects the upper end of this lever with the arm 29 so that the rotation of the cam shaft in the direction indicated by the arrow imparts an oscillation to this folder and moves it into the position indicated in Fig. 5. The stationary folder 60 is mounted adjacent the folding wheel and is preferably continued in the form of a guard around this wheel being supported by suitable pins 61. The forward movement of the folder wheel when it is intermittently rotated brings the lower projecting end of the wrapper 20 into engagement with this stationary folder and forms the longitudinal fold 109 in the wrapper, the oscillating folder 28 being withdrawn about this time. This fold is held down by the guard or continuation of the stationary folder until the partially wrapped article has made a half revolution and is brought into alignment with the coöperating mold in the tucker wheel 81. This tucker wheel is preferably provided with tucker plates 53 secured at either side of each of the molds, as indicated in Figs. 6, 7 and 8. The ejector operated in the manner described throws the plungers 48 to the left and thus transfers the partially wrapped article from the folding wheel into the coöperating mold of the tucker wheel, this movement causing the projecting ends of the wrapper to impinge upon the tucking plates 53 at the ends of the molds so that the top end fold 110 is thus formed in the wrapper at either end of the article. It will be noted that the stationary cams 94, 95 on the shafts of the mold wheels are so shaped that the spring pressed sides of the molds are released at the time when articles are inserted or discharged from the molds, while at other times the articles are gripped with the desired pressure by these movable sides. A suitable setter 27 is preferably provided secured to the frame and located in such position that the plungers 48 are brought into

the proper position as the molds are rotated into position to receive an article. This setter 27 consists of a fixed bar supported by the frame and extending into the path of the plungers.

The stationary tuckers 44 are secured to the sides 93 of the discharge chute 92. The oscillating tuckers 45 are secured to the tucker shaft 118, the arm 47 on this shaft being pivoted to the tucker bar 46 which is also pivoted to the sleeve of the arm 29 of the oscillating folder 28 so that the oscillating folder and the oscillating tuckers operate in unison, see dotted lines, Fig. 2. When the articles in the tucking wheel 81 are brought toward the discharge chute, the oscillating tuckers 45 are withdrawn into position indicated in Fig. 7 so as to be out of the path of the projecting wrapper ends. The further movement of the tucking wheel will under these conditions bring the projecting ends of the wrappers into engagement with the stationary tuckers 44 so as to form one of the side end folds 111 at either end of the article. Thereupon when the article is brought into alignment with the discharge chute, the oscillating tuckers 45 operate and form the opposite side end fold 112, as indicated in Figs. 8 and 11. At this time, the ejector operates and the ejector pin 64 engages the short pin 90 on the plunger 48 and moves this plunger outward, the pin 64 being accommodated by the slot 91 in the tucker plate 53, see Fig. 10. This forms the top end fold 113 at either end of the article and also forces the article into the discharge chute, pushing the preceding articles ahead of it.

It is, of course, understood that those familiar with this art may make many variations in the number, proportion and arrangement of parts of this machine, parts of the same may be used without employing the whole, and parts may be used in connection with other devices without departing from the spirit of this invention or losing the advantages of the same. I do not, therefore, desire to be limited to the details of the disclosure which has been made in this case, but

What I claim as new and what I desire to secure by Letters Patent is set forth in the appended claims.

1. In wrapping machines, a mold wheel having molds to receive articles, an auxiliary feeder to feed a wrapper strip, an intermittently gripping feeder for said strip, means to sever the same into separate wrappers, an intermittently operating aliner to aline said strip while the grip of said feeder is released and an intermittently operating looper between said feeder and said auxiliary feed to furnish slack in said strip while said aliner is operating.

2. In wrapping machines, an intermittently rotating folding wheel provided with molds, a feeder to supply articles to be wrapped, a

movable support adjacent said feeder, a movable guide to coöperate with said support, and a feed plate adapted to force articles into said molds while engaged by said support and guide.

3. In wrapping machines, a rotating folding wheel provided with molds, means to supply wrappers adjacent said molds, a feeder to supply articles adjacent said molds, a support located beneath the feeder to support articles, a movable guide located above said feeder, means for moving said support and said guide toward a mold on either side of an article to be wrapped by the folding wheel and a feed plate to engage said article and force the same into said mold.

4. In wrapping machines, a folding wheel having molds therein, a coöperating tucking wheel having molds therein, tucking plates secured to said tucking wheel adjacent the molds therein, plungers having convex working faces operating in the molds in said wheel to transfer articles, a discharge chute adjacent said tucking wheel and means to supply articles and wrappers to said folding wheel.

5. In wrapping machines a folding wheel having molds therein, a coöperating tucking wheel having molds, plunger rods in said wheels, plungers operating in said molds, said plungers being rigidly secured to either end of said plunger rods so that the opposite plungers in a wheel operate in unison, a discharge chute adjacent said tucking wheel and a pivoted ejector and a feed plate operating in unison to simultaneously feed a wrapper and an article into said folding wheel and eject the wrapped and tucked article from the tucking wheel.

40 6. In wrapping machines, a wrapping wheel having molds, plungers operating in said molds, plunger rods secured to said plungers on either side of said wheel, means to supply articles and wrappers to said wrapping wheel and an ejector and feed plate connected to operate in unison to force an article into said wrapping wheel and adapted to coact with the plunger rod to eject an article therefrom.

50 7. In wrapping machines, a wrapping wheel provided with molds, plungers having convex working faces operating in said molds, means to force articles and wrappers into said molds and folding means to fold said wrappers around said articles, and a fixed setter in the path of the plungers.

8. In wrapping machines, a wrapping wheel having molds, plungers having convex working faces operating in said molds, means to operate said plungers and means to force articles and wrappers into said molds, and a fixed setter in the path of the plungers.

9. In wrapping machines, a folding wheel having molds therein, a coöperating tucking wheel having molds, tucking plates secured

to said tucking wheel adjacent the ends of the molds therein and means to transfer articles and wrappers from said wrapping wheel into said tucking wheel to form folds in said wrappers by said tucking plates.

10. In wrapping machines, a folding wheel having molds therein, a coöperating tucking wheel having molds, tucking plates secured to said tucking wheel adjacent the molds therein and plungers in said molds in said folding wheel to transfer articles and wrappers from said folding wheel into said tucking wheel and to fold said wrappers by said tucking plates.

11. In wrapping machines, a wheel having substantially rectangular molds therein, substantially rectangular tucking plates secured to said molds adjacent the ends of the molds therein and means to force articles and wrappers into said molds to tuck the ends of said wrappers by said tucking plates.

12. In wrapping machines, a wheel having molds therein, tucking plates secured to said wheel adjacent said molds and means to force articles and wrappers into said molds to fold said wrappers by said tucking plates.

13. In wrapping machines, a wheel having a mold therein, a tucking plate secured immovably to said wheel adjacent said mold and means to force articles and wrappers into said mold and to tuck said wrappers by said tucking plate.

14. In wrapping machines, a folding wheel having molds, a coöperating tucking wheel having molds, a discharge chute coöperating with said tucking wheel, a stationary tucker adjacent said discharge chute, a movable tucker adjacent said chute, a movable folder adjacent said folding wheel and adapted to move simultaneously with said movable tucker, a stationary folder coöperating with said folding wheel, means to force articles and wrappers into said folding wheel and to transfer the same into said tucking wheel and said discharge chute and means to rotate said folding and tucking wheels.

15. In folding machines, a wrapping wheel having molds, a coöperating tucking wheel having molds, a discharge chute adjacent said tucking wheel, means to force articles and wrappers into said folding wheel and to transfer the same into said tucking wheel and said discharge chute, stationary tuckers adjacent said discharge chute and movable tuckers adjacent said discharge chute and means for moving said movable tuckers out of the path of said wrappers as said tucking wheel moves said wrappers into engagement with said stationary tuckers and thereafter moving said movable tuckers into engagement with said wrappers.

16. In wrapping machines, a wheel having molds therein, a discharge chute adjacent said wheel, means to feed articles and wrappers into said molds and to transfer them

into said chute, stationary tuckers adjacent said discharge chute to engage wrappers as said wheel rotates to bring a mold into alinement with said chute and movable tuckers adjacent said chute to operate upon wrapper ends in a mold in alinement with said chute, the sides of said chute engaging said wrappers as the article is transferred to said chute and forming folds therein.

10 17. In wrapping machines, a wheel having molds, means to force articles and wrappers into said molds, a discharge chute adjacent said wheel, a movable tucker adjacent said chute, means to withdraw said tucker from the path of wrappers as said molds are rotated into alinement with said chute and to operate said tucker to form a fold in a wrapper contained in a mold held in alinement with said chute.

20 18. In wrapping machines, an intermittently rotating wrapping wheel provided with molds, a feeder to supply articles to be wrapped adjacent said wrapping wheel, a movable support located below said feeder, a separate movable guide located above the feeder, means to hold said guide in disengaged position when said support is retracted and a feed plate to force articles between said support and said guide into said molds.

30 19. In wrapping machines, an intermittently rotating wrapping wheel provided with molds, a feeder to supply articles to be wrapped adjacent said mold wheel, a movable support adjacent said feeder, a movable guide to coöperate with said support to hold an article to be wrapped by the wrapping wheel, means to hold said guide in disengaged position until the article is fed into alinement with one of said molds, and means 40 to force said article between said support and said guide into said mold.

20 20. In wrapping machines, a movable mold, a feed belt to supply articles to be wrapped adjacent said mold, a movable support beneath said belt, a movable guide above said belt, said support and guide adapted to coöperate to hold an article, means to hold said guide in disengaged position when said support is retracted, means to move said support and guide forward toward said mold, and means to force an article between said guide and support into said molds.

50 21. In wrapping machines, a folding wheel having molds therein means to fold the wrappers around the articles in said mold, a coöperating tucking wheel having molds therein, tucking plates rigidly secured to said tucking wheel adjacent the ends of the molds therein and projecting into the path of the wrapper ends on articles fed into said molds and means to transfer articles and wrappers from said wrapping wheel into said tucking wheel to

form end folds in said wrappers by their engagement with said tucking plates.

22. In wrapping machines, a wheel having 65 a mold therein, a tucking plate rigidly secured to said wheel adjacent said mold and in the path of the wrapper ends of articles fed into said mold and means to force articles and wrappers into said mold to make end 70 fold in the said wrappers by their engagement with said tucking plate.

23. In wrapping machines, a wheel provided with molds, plunger rods in said wheel, plungers having convex working faces 75 secured to either end of said rods and operating in said molds, the said molds having spring-pressed pivoted sides, a cam on the shaft of said wheel and arms extending from the sides of said molds to engage said cams and automatically release said sides when said molds are in receiving or discharge position.

24. In wrapping machines, an intermittently rotating folding wheel provided with molds, a feeder to supply articles to be wrapped, a pivoted arm, a movable support carried by the arm, a movable guide also carried by the arm, and a feed plate to force articles into said molds while engaged by said support and guide.

25. In wrapping machines, a folding wheel having molds therein, plungers operating in said molds, a coöperating tucking wheel having molds, plungers operating in said molds, the working faces of said plungers being convex, a fixed setter carried by the frame and located in the path of the plungers, a discharge chute adjacent said tucking wheel, means to supply articles and wrappers to said wrapping wheel and to transfer them 95 into said tucking wheel and said chute.

26. In wrapping machines, a wrapping wheel having molds, plungers operating in said molds, plunger rods, secured to said plungers on either side of said wheel, means 105 to supply articles and wrappers to said wrapping wheel and a pivoted ejector and feed plate connected to operate in unison to force an article into said wrapping wheel and to eject an article therefrom.

27. In wrapping machines, a folding wheel having molds therein, a coöperating tucking wheel having molds, tucking plates rigidly secured to said tucking wheel adjacent the ends of the molds therein and projecting into the path of the wrapper ends and means to transfer articles and wrappers from said wrapping wheel into said tucking wheel to form folds in said wrappers by said tucking plates.
